Attorney

UNITED STATES PATENT OFFICE.

ROBERT DE REMER, OF ALCESTER, SOUTH DAKOTA.

FENCE-POST EXTENSION.

Application filed November 17, 1927. Serial No. 233,860.

This invention relates to fence post extensions and pertains more particularly to the type in which the extension is attached to the top of the post and at an angle thereto.

The primary object of the invention is to provide an extension which can be interchangeably used, namely to dispose the extension on either side of the post and upwardly therefrom, or to dispose same on either side of the post downwardly therefrom, to thus enable the extension to be adapted for the particular needs of the user, and to be changed from one disposition to another or others, as may be desired.

In the drawings:—

Fig. 1 is a side elevation of the invention applied to a fence post, the latter shown in fragment, and the various dispositions 20 of the extension being shown in dotted lines;

Fig. 2 is a top plan view of Fig. 1, and

Fig. 3 is a section on line 3—3 of Fig. 1.

In proceeding in accordance with the present invention, the extension 1, which 25 may be of cast steel or other metal, is preferably of cruci-form as depicted in Fig. 3 of the drawings, and is formed with an enlarged angular inner end 2 which latter is provided with an opening 3. The opening 30 3 extends through the top and bottom faces of the enlarged end 2 and is shaped in cross-section to conform to the particular cross-section of the post 4 that may be employed. Obviously, the opening 3 can vary in cross-section to correspond to that of the usual post 4 and by virtue of the opening extending through the upper and lower faces of the enlarged end 2, it will be noted that 35 the extension can be disposed in varying positions as illustrated in full and dotted lines in Fig. 1.

The side webs 5 and 6 of the extension are notched as indicated at 7 and 8 respectively, so as to receive the usual barbed wire 45 and its fasteners.

By referring to Fig. 1, it will be seen that the extension may be disposed to extend upwardly from the fence post 4 on either side thereof and by removing and 50 inverting the extension same may be likewise disposed on either side of the post 4 but extending downwardly at an angle from the latter.

The enlarged end 2 may be secured in position by any suitable means such as for instance by wire staples 9 or the like.

From the foregoing, it will be seen that with the present invention the extension may be used in a multiplicity of positions and at any time may be changed to various 60 positions within the limits above described, as desired.

When the extension is used to project upwardly from the fence post, the latter extends through the opening 3 from the bottom face thereof, and when the extension is used to project downwardly from the post, the latter projects through the opening from the top face of the opening, as shown in Fig. 1.

What is claimed is:—

1. In a fence post extension, a body having opposed notched longitudinal webs to engage barb-wire or the like, and an angular enlarged end on the body, said enlarged end having an opening extending through its upper and lower faces to receive the upper end of a fence post through either of said faces, the opening being formed so as to receive the post with the body disposed on either side of the post and extending either upwardly at an angle to the post or downwardly at an angle thereto.

2. In a fence post extension, a body having an angular enlarged end formed with an opening extending through its upper and lower faces to receive the upper end of a fence post through either of said faces, the opening being formed so as to receive the post with the body disposed on either side of the post and extending either upwardly at an angle to the post or downwardly at an angle thereto.

3. In a fence post extension, a body having an opening extending through its upper and lower faces to receive the upper end of a fence post through either of said faces, the opening being disposed at an angle to the longitudinal axis of the body so as to receive the post with the body disposed on either side of the post and extending either upwardly at an angle to the post or downwardly at an angle thereto.

In testimony whereof I affix my signature.

ROBERT DE REMER.
